SUPPORT AND TIE FOR CONCRETE-REINFORCING BARS.

1,143,323.

Specification of Letters Patent. Patented June 15, 1915.

Application filed March 25, 1914. Serial No. 827,118.

To all whom it may concern:

Be it known that I, GEORGE R. SCHOENTHALER, a citizen of the United States, residing at Chicago, Illinois, have invented a certain new and useful Improvement in Supports and Ties for Concrete-Reinforcing Bars, of which the following is a full, clear, and exact description, such as will enable others skilled in the art to which it appertains to make and use the same, reference being had to the accompanying drawings, forming part of this specification, in which—

Figure 1 is a perspective view of a combined concrete reinforcing bar support and tie of my improved construction. Fig. 2 is a side elevational view of the support and tie positioned for use on a pair of horizontally disposed crossed reinforcing rods. Fig. 3 is a side elevational view of the combined support and tie, the same being adapted for use in connection with vertically disposed reinforcing rods, as are used in walls and partitions. Fig. 4 is a perspective view of a key utilized in connection with the support and tie when the same is applied to vertically disposed reinforcing rods.

My invention relates generally to reinforced concrete construction and more particularly to a support and tie for the metal rods used in reinforcing concrete floors, ceilings, walls and the like.

In reinforcing concrete floors, ceilings and walls, it is desirable and in nearly all instances, essential that the reinforcing rods be supported in a plane above or away from the temporary flooring or form upon which the concrete is laid, and to this end, I have devised a comparatively simple, strong and inexpensive support and tie which is formed from a single piece of resilient wire and which can be readily combined with reinforcing rods so as to maintain the same a substantial distance above or away from the floor or form while the concrete in plastic condition is being poured or distributed thereupon.

The principal object of my invention is to provide a combined support and tie which can be applied to a pair of intersecting rods, and which will yieldingly support said rods, and at the same time tie the same together so that they will be held in proper form

while the concrete is poured or distributed upon the form for the floor or wall.

A further object of my invention is to provide a comparatively simple device in which is combined a pair of supporting legs, a pair of horizontally aligned seats for one of the reinforcing rods, and a pair of resilient arms which can be readily bent downward over a transverse fulcrum, which latter is a part of the combined support and tie, thus imparting to said arms sufficient resiliency so that the same firmly engage and grip one of the reinforcing rods, thereby holding the same against longitudinal movement and at the same time effectually tying the crossed rods to each other and the device to said rods.

With the above and other objects in view, my invention consists in certain novel features of construction and arrangement of parts, hereinafter more fully described and claimed.

As shown in the drawings, my improved device is constructed from a single piece of resilient wire, the central portion of which is bent so as to form a short horizontally disposed member 10, which when the device is in use, is positioned across the top of the upper one of a pair of crossed reinforcing rods. From the ends of this centrally arranged transverse member 10 the wire extends laterally and downwardly as designated by 11, thence upwardly and outwardly as designated by 12, and from the upper ends of these portions 12, the wire is bent downwardly as designated by 13 into a plane lying parallel with the plane occupied by the portions 12. From the lower ends of the portions 13 the wire is bent upwardly as designated by 14, thence downwardly as designated by 15, and thence upwardly and laterally as designated by 16. The portions 14 lie parallel with and immediately against the portions 13, thereby forming a pair of legs A, the lower ends of which are adapted to rest on the floor or form when the device is in use. The portions 15 lie parallel with and immediately against the portions 12, and the portions 16 lie parallel with and immediately against the portions 11. Between the lower ends of the parallel portions 11 and 16 and 12 and 15 are formed curved seats B which

are in horizontal alinement with each other, and which receive the lower one of the crossed reinforcing rods. The portions 16 overlie the ends of the central transverse member 10 and from said member the end portions of the section of wire of which the device is formed extend outwardly and upwardly as designated by 17, thereby forming resilient arms, the outer ends of which 10 terminate in transversely disposed hooks 18.

When my improved support and tie is used in connection with horizontally disposed reinforcing rods the lower ends of the legs A rest upon the floor or form as seen in Fig. 2. The lower reinforcing rod X is positioned upon the seats B and the upper reinforcing rod Z rests upon said lower rod X and passes between the upper portions of the parallel sections 11 and 16. The transverse member 10 rests on top of the upper rod Z, and the spring arms 17 which normally occupy the position shown by dotted lines in Fig. 2 are bent downward so that the hooks 18 are engaged beneath said upper rod Z. As these arms 17 are bent downward they fulcrum upon the transversely disposed member 10 and as a result the resiliency of said arms is materially increased and such increased resiliency causes the hooks 18 to engage the rod Z with considerable pressure, thereby holding the same against longitudinal movement and tying it to the lower rod X. Normally, the legs A support the reinforcing rods as shown in Fig. 2, but under weight of a workman or a wheelbarrow load of concrete, said legs will yield to a certain degree, and after this weight has been removed the resiliency of the legs will return the bars to their normal positions. This is a decided advantage over those forms of supports and ties which are constructed of sheet metal and the like, and which crush down under weight, thereby permitting the reinforcing rods to lie directly upon the surfaces of the floor or form.

Where the device is intended for use in connection with reinforcing rods in walls and the like, the legs A are made slightly longer than in the other form of the device, and thus the outer ends of said legs extend beyond the upper or outer one of the reinforcing rods. This forms a pair of semi-circular seats S at the lower ends of the legs A and inserted through these seats is a wedge or key 19 preferably formed of sheet metal and which, when driven in firmly, ties the device to the reinforcing rods.

Ordinarily the spring arms 17 are sufficient to clamp the device to the bars, and this wedge is only an additional precaution to hold the parts in proper shape when concrete is dumped from an unusual height, and there is tendency to jar the bars loose from one another and from the tie.

A combined support and tie of my improved construction is comparatively simple, can be cheaply manufactured, is easily applied to reinforcing rods, and provides efficient means for tying said rods together and holding the same in proper position upon the form or false work which receives the concrete.

It will be readily understood that minor changes in the size, form and construction of the various parts of my improved support and tie may be made and substituted for those herein shown and described, without departing from the spirit of my invention, the scope of which is set forth in the appended claims.

I claim:

1. A device of the class described comprising a pair of parallel resilient arms, hooks on the outer ends thereof, a transversely disposed support arranged beneath the central portions of said arms, and resilient supporting legs at the lower ends of said parallel arms.

2. A device of the class described constructed of a single piece of wire, the central portion of which is bent into substantially inverted U-shape for engagement over a reinforcing rod, the section of wire being bent from the ends of the legs of said U-shaped portion to form substantially upright supporting legs which are spaced a sufficient distance apart to receive a reinforcing bar, the end portions of the section of wire being extended from said upright legs to form resilient rod engaging arms which overlie the transverse member of the inverted U-shaped portion of the device, rod engaging hooks on the ends of said resilient arms, and a pair of substantially U-shaped seats formed between the upright legs and the rod engaging arms, which seats are adapted to receive a reinforcing rod.

3. A device of the class described formed of a single piece of wire bent to form a pair of upright supporting legs which are spaced apart a sufficient distance to receive a reinforcing bar, a transversely disposed section adapted to rest on top of the reinforcing bar which is positioned between said legs, the wire between said legs and the transversely disposed section being bent into substantially U-shape to form a pair of seats for a reinforcing bar which is positioned beneath and at right angles to the reinforcing bar which is positioned between the legs, and a pair of resilient arms extending across and beyond the transversely disposed member, which arms terminate in hooks which are adapted to engage beneath the reinforcing bar which is positioned between the legs.

4. A device of the class described formed of a single piece of wire bent to form a pair of substantially upright resilient supporting legs spaced apart a sufficient dis-

tance to receive a reinforcing rod, a pair of parallel resilient arms projecting laterally from the supporting legs, rod engaging hooks on the ends of said resilient arms, 5 and a transversely disposed member forming a part of the device and positioned beneath the resilient arms to form a fulcrum therefor.

In testimony whereof I hereunto affix my signature in the presence of two witnesses, 10 this 18th day of Feb., 1914.

GEO. R. SCHOENTHALER.
